UNITED STATES PATENT OFFICE.

WILLIAM S. HOVEY, OF THREE RIVERS, MICHIGAN, ASSIGNOR TO SHEFFIELD CAR COMPANY, OF THREE RIVERS, MICHIGAN.

RAILWAY MOTOR-CAR.

No. 866,136.

Specification of Letters Patent.

Patented Sept. 17, 1907.

Application filed March 25, 1907. Serial No. 364,249.

To all whom it may concern:

Be it known that I, WILLIAM S. HOVEY, a citizen of the United States, residing at the city of Three Rivers, county of St. Joseph, State of Michigan, have invented 5 certain new and useful Improvements in Railway Motor-Cars, of which the following is a specification.

This invention relates to improvements in railway motor cars.

It relates particularly to an improved railway motor 10 car adapted to be driven by an explosion engine.

The main object of this invention is to provide an improved railway motor car adapted to be driven by an explosion engine.

Further objects, and objects relating to details of 15 construction, will definitely appear from the detailed description to follow.

I accomplish the objects of my invention by the devices and means described in the following specification.

20 The invention is clearly defined and pointed out in the claims.

A structure embodying the features of my invention is fully illustrated in the accompanying drawing, forming a part of this specification, in which,

25 Figure 1 is a detail side elevation of my improved railway motor car, one of the side doors for the engine housing being removed. Fig. 2 is a detail transverse vertical section through the car body showing the central arrangement of the engine. Fig. 3 is a detail side elevation showing the arrangement of the seats at the rear of the engine. Fig. 4 is a detail end elevation of the engine housing.

In the drawing similar letters of reference refer to similar parts throughout the several views.

30 Referring to the drawing, 1 is the floor of the car body, which is supported on suitable longitudinal sills as 8-8. The car illustrated is of the open type, the roof being supported by the side posts 2. In the floor of the car body is an opening or well 9, through which the engine 4 is arranged. The engine is provided with suitable driving connections to the traction wheels as 10, the details of which are not here illustrated, as they form no part of this invention.

The well or opening 9 is provided with a housing 5 for the engine, the top of which is adapted to form a platform or deck, it being intended that this platform or deck may be used for baggage or the like.

The engine is arranged in the longitudinal center of the car and seats as 3 are preferably provided at each side of the housing therefor. The housing is provided 50 with a suitable door 6 in its front and also doors 7 at each side, through which access may be had to the engine. The doors 7 at the sides of the housing are located between the seats 3 as clearly appears in Fig. 1. By this arrangement, the engine, which is of the explosion 55 type, is conveniently located, and the floor of the car body may be as low as is practicable. The housing prevents the exhaust from the engine entering the car, thereby obviating the annoyance which would otherwise be occasioned. At the rear of the housing 51 I provide a plurality of seats, only one being illustrated in the accompanying drawing, as their arrangement will be readily understood.

I have illustrated and described in this application my improved railway motor car in detail in the form 65 preferred by me on account of its structural simplicity and economy. It will, however, be readily understood that it is capable of considerable variation in structural details without departing from my invention.

Having thus described my invention, what I claim 70 as new and desire to secure by Letters Patent, is:

1. A railway motor car comprising a car body, having an engine well or opening through the floor thereof; an engine arranged through said opening; a housing for said well or opening, the top of said housing being adapted to 75 form a deck or platform; doors in the sides and front end of said housing whereby access to said engine may be had, said housing being located so as to provide space for the motorman in front thereof; and seats at each side and to the rear of said housing, the said side doors of said housing being located between the seats at the sides thereof, substantially as described.

2. A railway motor car comprising a car body, having an engine well or opening through the floor thereof; an engine arranged through said opening; a housing for said well or opening; doors in the sides and front end of said housing whereby access to said engine may be had, said housing being located so as to provide space for the motorman in front thereof; and seats at each side and to the rear of said housing, the said side doors of said housing 85 being located between the seats at the sides thereof, substantially as described.

In witness whereof, I have hereunto set my hand and seal in the presence of two witnesses.

WILLIAM S. HOVEY. [L. S.]

Witnesses:
